UNITED STATES PATENT OFFICE.

CARL O. ENGSTROM, OF SACRAMENTO, CALIFORNIA.

SAFETY-RAZOR.

1,373,874.

Specification of Letters Patent.

Patented Apr. 5, 1921.

Application filed April 21, 1920. Serial No. 375,425.

To all whom it may concern:

Be it known that I, CARL O. ENGSTROM, a citizen of the United States, residing at Sacramento, in the county of Sacramento and State of California, have invented certain new and useful Improvements in Safety-Razors, of which the following is a specification.

The present invention relates to improvements in safety razors, and more particularly to that type of razor illustrated in Letters Patent No. 1,226,322, granted to me on the 15th day of May 1917.

The principal objects of the present invention are to provide a safety razor construction, wherein the guard and blade are capable of adjustment one relatively to the other, enabling the user to shave lightly or closely without in any manner flexing the blade or guard; a further object is to provide the construction wherein the blade is held in operative position by a simple yieldable clamp, easily applied and removed from operative position. Another object is to provide a construction which is capable of being easily and quickly dried and cleaned after use, one using a blade of simple construction, and a razor which is capable of being manufactured at little cost.

With the above mentioned and other objects in view the invention consists in the novel construction and combination of parts, hereinafter described, illustrated in the accompanying drawings, and particularly set forth in the claims hereto appended; it being understood that various changes in the form, proportion, size, and minor details of construction may be resorted to without departing from the spirit or sacrificing any of the advantages of the invention.

To more fully comprehend the invention reference is directed to the accompanying drawings wherein—

Figure 1, is a view in plan of the preferred embodiment of my invention.

Fig. 2, is a view in side elevation.

Fig. 3, is a longitudinal sectional view taken on line 3—3 of Fig. 1 viewed in the direction of the arrows.

In the drawings, 1 indicates a handle forked at one end providing the head mounting arms 2, which carry at their ends the outwardly disposed alined fulcrum pins 3.

The fulcrum pins 3, are received in openings 55 near the ends of the end members 4 of the

head 5. The end members 4 are held together by a connecting plate 6 arranged with its faces spaced from the longitudinal side edges of the end members 4, with its longitudinal side edges intermediate the ends of said end members 4. Near the outer end of the head 5, the side plates 6 are connected by a cylindrical pin 7 providing a fulcrum about which one end of a blade supporting bed 8 is bent as at 9, the main portion of said bed 8 lying between the end members 4 and disposed in substantial alinement with the lower edges of said end members 4.

The terminal or free edge 8' of said bed 8 is provided at opposite ends with the blade limiting or retaining fingers 10, curved slightly downward toward the lower edge of end members 4, providing an abutment against which the ends of the cutting edge 75 of a blade 12 contact.

The blade 12 is positioned in the holder between the end members 4, with one side or surface flat against and with its cutting edge 13 projected slightly beyond the free edge 8' of said blade supporting bed 8. When in this position the cutting edge 13 of the blade is prevented from further movement beyond the edge of the supporting bed by contact at opposite ends with the fingers 10.

To hold the blade in operative position as illustrated and described, means are preferably employed comprising a spring retaining clamp 14, formed of a flat piece of spring material bent to a substantial U shaped configuration in end elevation. The retaining clamp 14 is of a width substantially equal to the distance between walls of the head, and the legs 15 and 16 thereof are of a depth sufficient to extend over the connecting plate 6 and the bed 8, when the clamp is in position.

To retain the clamp in operative position, as in the drawings, I prefer to employ a tension lever 17 fulcrumed relatively to the free end of the leg 15 on a pin 18. The foot 19 of the lever is adapted on the downward movement on the handle 20 of the lever to a substantially closed position, to have frictional contact with the cutting blade 6, and places said spring under tension.

The blade guard is preferably mounted in the following manner:

A guard plate 21 connects the ends of the end members 4 at their inner ends and the

upper portion of said plate is curved upwardly and rearwardly toward the handle 1 terminating in a flange 22.

The lower inner edge of the guard plate 5 is provided throughout its length with guard teeth 23 which lie in a plane parallel with and in spaced relation to the operative field of the cutting edge of the blade 12.

It will be apparent that the guard teeth 10 23, lie in advance of the cutting edge 13 of the blade 12 when the razor is in use, and all of said guard teeth are approximately in alinement with the pivotal connection between the handle and head.

15 To change the position of the cutting edge 13 of the blade 12 relatively to the teeth 23 to enable the user to shave lightly or closely I prefer to use the following mechanism: Extending across the head and pivoted at 20 its opposite ends as at 24 in the end members 4 at a point near the free end of the bed 8 is an operating cam 25 lying beneath the bed 8. The cam 25 is provided at this end passing through one of said end plates 25 with a lever 26 having spring connection with and movable over a number of teeth 28 formed on the outer surface of the end of plate 21, as clearly illustrated in Figs. 1 and 2 of the drawings. It will be readily understood that axial movement imparted to the cam 25 will change the position of the cutting edge 13 of the blade 12 relatively to the guard teeth 23.

To assist in maintaining the handle 1 in alinement with the plane of blade 12 I prefer to employ a spring 27 carried by the handle 1 and contacting with the flange 22 extending rearwardly from the guard plate 21.

40 As in my former patent the present razor head is pivoted on a line approximately parallel with the edge of the blade 12 and guard teeth 23. It will be understood that the raising of the lever 17 releases the tension 45 on the spring clip permitting the same to be readily removed from the frame and enabling the blade 12 to be removed from the bed 8.

The above set forth construction enables 50 me to manufacture a razor at little cost and at the same time to provide a construction wherein the operator by moving the lever 26 over the teeth 28 will swing the cutting edge of the blade across the guard teeth 23 55 and adjust the razor for a light or close shave.

I claim:—

1. A safety razor comprising a frame providing a head, a handle connected therewith, 60 a bed pivotally mounted within the frame,

a guard carried by the frame adjacent one edge of said bed, a blade supported by said bed and arranged with its cutting edge overlying the edge of the bed and lying adjacent to said guard, means for holding said blade to the bed, and means for adjusting the bed on its fulcrum to swing the cutting edge thereof relatively to the guard. 65

2. A safety razor comprising a frame providing a head, a handle connected therewith, 70 a blade carried by the head and arranged with its cutting edge facing said handle, a toothed guard arranged parallel with and in advance of the cutting edge of said blade with the teeth facing said cutting edge, and 75 means for moving the cutting edge of said blade across said guard.

3. A safety razor comprising a frame providing a head, a handle connected therewith, 80 a blade supporting bed pivotally mounted to said head, a guard facing said bed, a blade resting on said bed with its cutting edge parallel with said guard, a cam for coöperating with the bed for moving the same across the guard, and a spring clamp for 85 retaining the blade to said bed and the bed in contact with the cam.

4. A safety razor comprising a frame, a blade supporting bed carried thereby, a guard arranged in advance of and with its teeth facing the free edge of said bed, a blade resting on said bed with its cutting edge facing said guard, a spring clip substantially U shaped in end elevation for extending over opposite sides of said bed, a 95 lever for placing said clamp under tension, and a handle connected with the frame.

5. A safety razor comprising a frame, a handle pivotally connected at one end thereto, a guard carried by the frame and arranged with its teeth approximately in alinement with the fulcrum connection between said handle and frame, a bed pivotally mounted in the frame to swing on an axis parallel with the fulcrum point of the handle, and disposed with its free edge adjacent to said guard teeth, a blade resting on said bed with its cutting edge adjacent said guard teeth, a plate within said frame above said bed, a spring clamp embracing 110 said bed and plate, a lever associated with the clamp for bearing on the plate, and a cam coöperating with the bed for swinging the same against said spring tension to move the cutting edge of the blade across the 115 guard teeth.

In testimony whereof I have signed my name to this specification.

CARL O. ENGSTROM.
